(57) **CLAIM**

The ornamental design for an earphone case, as shown and described.

DESCRIPTION

FIG. 1 is a top perspective view of an earphone case, showing my design.

FIG. 2 is a bottom perspective view thereof.

FIG. 3 is a front elevation view thereof.

FIG. 4 is a rear elevation view thereof.

FIG. 5 is a left side elevation thereof.

FIG. 6 is a right side elevation thereof.

FIG. 7 is a top plan view thereof.

FIG. 8 is a bottom plan view thereof; and,

FIG. 9 is a perspective view of the earphone case in an open state.

The dashed broken lines depict portions of the earphone case and form no part of the claimed design. The dot-dash broken lines define boundaries of claimed design and form no part of the claimed design.
